ATTORNEY

UNITED STATES PATENT OFFICE.

AUGUST VOGES, OF CHICAGO, ILLINOIS.

METHOD OF PREPARING SOAP FOR USE.

Application filed May 5, 1919. Serial No. 294,643.

To all whom it may concern:

Be it known that I, AUGUST VOGES, a citizen of the United States, and a resident of Chicago, Cook County, Illinois, have invented a certain new, useful, and Improved Method of Preparing Soap for Use, of which the following is a specification.

There is still some controversy as to the exact causes and reactions that result in the 10 cleansing action of soap, but there are two generally accepted theories advanced as to the cleansing properties of soap. One such action is the emulsifying action, for it has been found that when an insoluble oil, such 15 as kerosene, for example, is shaken in water it is divided into a large number of minute globules, which, however, so soon as the shaking action is stopped, begin to run together and finally unite to form a layer of 20 the oil separate and distinct from the body of the water. If, however, a dilute soap solution be shaken together with an insoluble oil, such as above stated, the minute globules formed do not run together after 25 the shaking action has stopped, but on the contrary, remain permanently suspended in the solution, the reason for this being, that each minute droplet or globule of oil is surrounded entirely by a covering of the dilute 30 soap solution and the droplets are thereby prevented from contacting one with the other and thus running together. It is this surrounding action of the dilute soap solution when applied to material having a 35 greasy or oily substance therein that permits of the article to be cleansed by washing out the grease particles. The solution, in order to do its best work, should be a dilute solution.

40 Another cleansing action attributed to soap is that of the adsorption of colloidal matter, for example, when a solution containing a colloidal substance is shaken with the finely pulverized charcoal, the colloidal substance adhere to the surface of the powder.

45 In other words, there is a tendency to cohesion between the colloidal in the soap solution and the particles of a fine powder. As 50 the articles of fine dirt are comparatively few in the article or surface to be cleansed, as compared to the soap solution, the colloidal particles carry off the dirt. That is to say, the dirt is removed by adsorption into the soap solution.

Whether the above or other theories are the true explanations of the cleansing action of soap I have discovered that it becomes possible to cleanse a much larger surface with a much smaller quantity of soap 60 when the soap is broken up into very minute particles and that the general action of cleansing is greatly facilitated, and made much more thorough.

It is an object of my invention to provide 65 a method whereby it shall be possible to make a given quantity of soap perform more work as a cleansing agent, and whereby it shall be possible to cleanse more rapidly, more thoroughly and more conveniently. 70

Another object of my invention is to provide a method of preparing soap for use in such manner that it shall be possible with a given number of lavatories in a large factory, to enable a larger number of workmen 75 to wash within a given time.

My invention consists generally in the method whereby the above named objects, together with others that will appear hereinafter, are attainable and my invention 80 will be more readily understood by reference to the accompanying drawings which illustrate what I consider at the present time to be the best embodiment thereof.

In said drawings, Fig. 1, is a sectional 85 elevation of a wash basin equipped with apparatus for producing my invention. Fig. 2, is a front elevation of a wash basin and apparatus shown in Fig. 2.

My invention may be carried out in a 90 number of different ways and by the use of widely different apparatus, but inasmuch as the invention probably finds its greatest use in large manufacturing establishments where it is customary to provide liquid soap 95 for washing purposes, I shall describe my invention in conjunction with liquid soap and also as applied to an ordinary trough-like wash basin such as are usually found in factories.

100 Referring to the drawings; 1, represents a trough-like wash basin provided with a plurality of spaced faucets 2, enabling the basin to accommodate a number of people. In the present instance, I hang upon the 105 back plate 3, of the basin a shelf-like member, 4, by means of spaced supporting members 5, thereon. The shelf-like member 4, as here shown is provided with a basin-like portion, 6, upstanding from which will be 110

found a concave portion, 7. The shelf 4, is provided with an outward extension 8, which forms a support for a jar or receptacle, 9, in which liquid soap, 10, is contained. The jar, 9, is provided at the top with an apparatus corresponding in its general construction to an air brush. That is to say it is provided with a cover, 11, on which is supported a gun, 12, having an air supply pipe, 13, at one end and a nozzle 14, at the other. The connection 15, is a pipe such that when air is admitted to the barrel of the gun as by pressing the trigger, 16, the liquid soap 10, in the jar, 9, is forced upwardly through the vertical pipe, 17, and out of the nozzle, 18, at which time it is engaged by a blast of air at that time being projected from nozzle 14, of the gun 12. As the air emerges under high pressure the liquid soap discharging from the nozzle, 18, is broken up and the small particles are rapidly carried forward by the air stream and are projected with great force against the concave face 7, of the shelf 4. The droplets or globules of soap in their passage from the nozzle, 18, to the surface 7, are somewhat atomized before reaching the surface, 7, so that upon impingement therewith, the soap is converted into a fine lather and by gravity flows downwardly into the receptacle, 6. The gun is operated until the desired lather indicated at 19, is secured. The surface area of the lather is infinitely greater than that of the soap used and as a result when a quantity of lather is taken in the hand and brought into contact with the water the cleansing action is almost instantaneous since the dilute soap solution is practically instantaneously formed and in turn envelops or absorbs the grease or dirt with which it comes into contact. Not only is it possible by this means to wash or cleanse more rapidly, but it is also possible to cleanse more thoroughly and with the use of but a fraction of the soap required.

when soap is applied directly in unlathered form.

The surface, 7, is made concave simply to prevent the soap from being thrown away when projected against the surface 7, with great force.

I have not described the projecting apparatus in detail for the reason that almost any air brush or device used for the spraying of liquid materials may be employed. Such devices are of well known construction and can be purchased in the open market.

Inasmuch as this disclosure will suggest to others modified means whereby the substantial objects of my invention may be attained, I do not wish to be limited to the apparatus herein shown, or to the precise steps or sequence thereof, except only as may be necessary by the limitations in the hereunto appended claims.

I claim:

1. The method of preparing soap for use by first converting the soap into a lather for subsequent use that consists in providing a liquid soap, in progressively discharging small quantities of the liquid soap into an expansive air jet and thereby breaking the soap up into a fine and copious lather having considerable inherent stability.

2. The method of preparing soap for use by first converting the soap into a lather for subsequent use that consists in providing a liquid soap, in progressively discharging small quantities of the liquid soap into an expansive air jet, thereby breaking the soap up into a fine and copious lather having considerable inherent stability, and in thereafter impinging the resulting product upon a wall and by impact further breaking up and stabilizing the lather.

In testimony whereof, I have hereunto set my hand, this 29th day of April, 1919.

AUGUST VOGES.
